UNITED STATES PATENT OFFICE.

GARFIELD O. THOMPSON, OF SANBORN, NORTH DAKOTA.

STAMP-AFFIXING MACHINE.

No. 857,499.

Specification of Letters Patent.

Patented June 18, 1907.

Application filed May 2, 1906. Serial No. 314,806.

To all whom it may concern:

Be it known that I, GARFIELD O. THOMPSON, a citizen of the United States of America, residing at Sanborn, in the county of Barnes and State of North Dakota, have invented new and useful Improvements in Stamp-Affixing Machines, of which the following is a specification.

This invention relates to stamp affixing machines, the object of the invention being to provide a complete and effective machine by means of which an entire sheet of stamps may be placed in the machine and fed to the proper affixing position one or more at a time, according to the number required, moistened, separated from the sheet, and pressed upon the envelop, the machine being operated by hand and the mechanism operating automatically to attain the result above stated.

With the above and other objects in view, the nature of which will more fully appear as the description proceeds, the invention consists in the novel construction, combination and arrangement of parts hereinafter more fully described, illustrated and claimed.

In the accompanying drawings, Figure 1 is a front elevation of a stamp affixing machine embodying the present invention. Fig. 2 is a rear elevation of the same. Fig. 3 is an end view of the machine. Fig. 4 is a detail end view of the stamp sheet clamping mechanism. Figs. 5 and 6 are detail elevations of the mechanism for holding the carriage and tripping the same prior to its return movement. Fig. 7 is a sectional view of the clutch and pinion mechanism. Fig. 8 is a sectional elevation on the line 8—8 of Fig. 7. Fig. 9 is a longitudinal section through the moistening roller.

The stamp affixing machine comprises a supporting base 1 which may be mounted upon suitable legs 2. Extending upward from the base and secured rigidly thereon is a standard 3, the upper end of which is extended to form a curved arm 4 having at its end a guide 5 for a vertically movable plunger 6.

The plunger 6 is provided at its upper end with a head or hand piece 7 and carries at its lower end a platen 8 of any desired size or area to the lower face of which is secured a pad 9 which is adapted to come in contact with the printed sides of the stamps and

press the gummed side thereof against the underlying envelop or card. The plunger and platen are normally upheld by means of a platen retracting spring 10, one end of which is connected to the platen and the other end to a bracket or lug 11 on the guide 5, as shown in Figs. 1 and 3.

Connected to the platen 8 and extending downward therefrom is a stamp cutter comprising the oblique shearing elements 11^a and 12 disposed at right angles to each other and operating in line with the right angularly disposed rows of perforations in the stamp sheet so as to sever one or more stamps from the sheet as the platen descends. These shearing cutters are provided with shanks 13 which are secured to two sides of the platen 8, as indicated in Fig. 3.

Arranged beneath the platen 8 is a vertically movable table 14, the leg 15 of which extends downward through a bearing or guide 16 supported by a bracket 17 on the machine frame, as clearly shown in Fig. 3. Operatively connected to the lower extremity of the leg 15 is a table operating lever 18 which is fulcrumed at 19 on a post or extension 20 carried by the bracket 17, the rear end of said lever having pivotally connected thereto at 21 a connecting rod 22 which extends upward and has its upper end attached to an arm 23 extending backward from the plunger 6, whereby in each upward and downward movement of the plunger 6 and the platen 8, the table 14 is moved in an opposite direction, the table moving upward to meet the platen as the latter moves downward and the table forming a support for the envelop or card and the stamps as they are pressed on the envelop or card by the platen.

The connecting rod 22 is provided at one end, preferably the upper end, with a reduced shank 24 which works through an opening in the plunger arm 23, while between said plunger arm and a shoulder 25 on the connecting rod 22 is a spring 26 in the form of a compressible coil, whereby the table 14 is adapted to yield downward slightly when excessive pressure is brought to bear on the plunger 6 in the operation of affixing the stamps. The table may be of any desired size and is provided with side and end gages 27 and 28 respectively, to assist in holding the envelops or cards in proper position to receive the stamps.

29 designates a stamp sheet roll-holder which is preferably of rubber so as to obtain the necessary frictional hold on the stamp sheet, said roll-holder being mounted on a 5 shaft 30 journaled in suitable bearings at the opposite ends of a carriage 31, the shaft being provided at each end with a knob 32, whereby it may be turned for rolling the stamp sheet upon the roller or feeding the 10 same off of the roller to a position beneath the platen 8. At various intervals along the length of the roller 29 are spring clips 33 which extend around the major portion of the circumference of the roller, as shown by 15 dotted lines in Fig. 3, an opening being left between the extremities of the clips toward the front of the machine to enable the stamp sheet to be fed on to the roller and fed therefrom. These spring clips are secured to the 20 carriage at one end, as shown at 34, the opposite ends thereof being left free and deflected outward, as shown at 35. One edge of the stamp sheet is inserted into the clips and into engagement with the bottom of the 25 roller 29, after which the roller is turned until the entire stamp sheet is wound thereon within the clips, the direction of rotation of the roller being reversed to feed the stamps outward again between the platen and table 30 for a purpose which will hereinafter appear.

The forward portion of the carriage 31 is provided with a projecting rail 36 upon which rests the inner end of a presser roll 37 which is journaled on a shaft 38 carried by 35 the short arm 39 of an elbow lever fulcrumed at 40 on a bracket 41 forming a fixed part of the machine frame, the other or longer arm 42 of said elbow lever being acted upon by a spring 43 which operates to hold the presser 40 roll 37 against the guide rail 36 and also against the printed sides of the stamps.

44 designates a stop in the form of a screw passing through a lug 45 on the bracket 41 and serving to limit the movement of the lever arm 42 so as to hold the presser roll 37 in 45 exactly the proper position and relation to the guide rail 36 and the stamps.

Just beneath the presser roll 37, there is arranged a stamp moistening roller 46 which 50 is journaled on a shaft 47 carried by the short arm 48 of an elbow lever fulcrumed at 49, the longer arm 50 of said lever being acted upon by a spring 51 which operates to hold the roller 46 up against the bottom of 55 gummed side of the stamp sheet, 52 designating a stop in the form of a screw adjustable through a lug 53 on the bracket 41 for limiting the movement of the lever arm 50 and holding the moistening roller 46 in 60 proper relation to the stamp sheet for moistening the gummed side thereof preparatory to cutting the stamp from the sheet and pressing the same on the envelop or card.

In order to provide for inserting the outermost rows of stamps between the rollers 37 and 46, I provide a pair of detents 54 and 55 which engage shoulders on the levers 42 and 50 respectively, as shown in Fig. 1, when said levers are rocked back to move the rollers 37 and 46 apart, said detents being provided with lever extensions 56 and 57 to facilitate engaging the detents with and disengaging the same from the shoulders on the levers 42 and 50. The rollers 37 and 46 are first moved 70 apart and then locked by means of the detents, after which the edge of the stamp sheet is fed outward between said rollers by manipulating one or the other of the knobs 32. The stamp sheet is fed outward until the 80 outermost row of stamps is in line with the platen and the perforations in line with the shearing cutter 11^a; then, as the plunger is moved downward, the cutter 11^a severs one or more stamps of the outermost row from 85 the main body of the sheet, while the transversely disposed cutter 12 removes one or more stamps from the outermost row just before the platen 8 descends and presses the moistened stamp or stamps upon the envelop 90 or card lying on the table 14. After the stamp sheet has been fed outward in the manner just described, the detents 54 and 55 are released or unlocked, whereupon the rollers 37 and 46 engage upon and beneath the outermost row of stamps, and the stamps are 95 fed along between said rollers 37 and 46 and the gummed side thereof moistened as the carriage moves lengthwise.

58 designates a clamp in the form of a bar 100 extending practically the entire length of the carriage and having at its opposite ends arms 59 which are journaled on a shaft 60 carried by bracket arms 61 at opposite ends of the carriage. The clamp 58 is held downward 105 by means of one or more springs 62 connected with the bracket arms 61, as shown in Fig. 4. To lift the clamp 58 preparatory to feeding the stamps upon and off the roll 29, I provide levers 63 fixed to the arms 59, as 110 shown in Fig. 4, and other levers 64 pivotally mounted at 65 on the arms 59 and carrying catches 66 which engage shoulders 67 on the bracket arms 61, the catches 66 being urged toward the shoulders 67 by means of springs 115 68. By rocking the levers 64 toward the levers 63, the catches 66 are thrown out of engagement with the shoulders 67, thus allowing the clamp 58 to be moved upward to release its hold on the stamp sheet. At all 120 other times the clamp 58 holds the stamp sheet firmly down upon the carriage with one row of stamps projecting beyond the clamp to be engaged and operated upon by the platen and cutters, in the manner hereinabove described.

The carriage is provided on its under side with oppositely arranged pairs of runners 69

which move lengthwise along carriage track rails 70 supported at their opposite ends by brackets 71 on the machine frame, and the carriage, after having been fed to one limit of its movement, is returned to the initial point of movement by means of a carriage actuating tape or band 72 preferably in the form of an elastic strip, one end of which is secured to the carriage at the point 73, while the opposite end is secured at 74 to one of the brackets 71. The mechanism for feeding the carriage along step by step a distance equal to the width of one stamp, embodies a plunger actuated rack bar 75 which is pivotally connected at the point 76 and the plunger arm 23, said rack bar being extended above the pivot 76 provided with a lever arm or extension 77. The rack bar works up and down with the plunger and in its up and down stroke it actuates a pinion shaft 78 which is illustrated in detail in Figs. 5 to 8 inclusive. This shaft is divided, as shown in Fig. 7, or, in other words, comprises two relatively movable and rotatable sections, one of which fits into the other. The main outer section is provided with a pinion 79 which engages a rack rail 80 extending lengthwise of the back of the carriage and secured thereto whereby, in the rotation of the shaft 78, the pinion 79 acts on the rack rail 80 to move the carriage lengthwise. Mounted on the outer section 81 of the pinion shaft is a clutch pinion 82 provided with a circumferential flange 83 which lies outside of the rack bar 75, as shown in Fig. 2, thereby forming a guide for the rack bar.

The section 81 of the pinion shaft extends from a hub or flange 84 and is mounted in an opening 81^a in the shaft 78, a bearing plate 88^a having secured to one side a disk 88 and at the opposite side a disk 88^b. Mounted between these disks is a clutch element 85 having oppositely disposed shoulders 85^a which are engaged by the inner ends of a pair of clutch dogs 86 normally pressed inward to engage said shoulders by means of springs 87 secured to the disk 88^b. The disks 88 and 88^b are fast on the shaft 78, while the clutch element 85 is movable upon said shaft relatively to the disks. It will thus be seen that the pinion 82 may be rotated in one direction by the downward movement of the rack bar 75 without imparting rotary movement to the pinion 79. In the reverse or upward movement of the rack bar 75, however, the clutch dogs 86 take up the clutch element or collar 85 and thereby impart rotary movement to the pinion 79 which thereby acts on the rack rail 80 to advance the carriage a distance equal to the width of a postage stamp. Extending alongside of the rack rail 80 is a notched bar 89, the notches 90 of which are arranged at a distance apart equal to the widths of the stamps. In connection with

the notched bar 89, a dog 91 is employed to interlock therewith, said dog being pivotally mounted at 92 on a bracket lug 93 extending laterally from the fixed standard 3, hereinabove described and as clearly shown in Figs. 5 and 6. The point of the dog is adapted to successively engage the notches 90 and is provided with an operating arm 94 which is connected by a link 95 with one arm of an elbow trip or release lever 96 fulcrumed at 97 on the standard 3, the longer arm of said trip lever receiving the pressure of a spring 98 secured to the standard 3 and acting to hold the point of the dog in engagement with the notched bar, as shown in Fig. 5. The lever 96 is also provided with a projecting shoulder 99 which, when the carriage reaches the final end of its throw, comes in contact with a stationary trip lever shift 100 which throws the lever 96 to one side and moves the dog 91 out of engagement with the notched bar, as shown in Fig. 6, whereupon the elastic band 72 acts on the carriage and returns the same quickly to its initial position. 101 represents the thumb piece or finger extension of the lever 96.

The moistening roller 46 embodies a hollow cylindrical body closed at opposite ends and provided with a multiplicity of perforations 102 communicating with the interior thereof and adapted to permit the water or other liquid contained in said roller to pass outward to the other surface of the roller whence it is taken up by an absorbent covering 103 surrounding the roller, as shown in Fig. 9, and distributed by said absorbent covering to the gummed sides of the stamps, as they are fed over the moistening roller.

104 designates a stopper or plug fitting in an opening in the moistening roller by means of which water or other liquid may be introduced into the roller.

In the operation of the machine, the stamp sheet is first fed on to the roll holder in the manner above described. The presser and moistening rollers are then separated and the stamp sheet is fed outward so as to enter the outermost row of stamps between the presser and the moistening rollers, the latter then being released and allowed to clamp the outermost row of stamps between them. The clamp 58 is also released and moved downward by the actuating springs to clamp the sheet of stamps firmly against the carriage. The envelopes or cards are now placed upon the table and fed successively into place beneath the plunger. The plunger is then operated successively and in each downward movement of the platen, one or more stamps is severed from the sheet just after being moistened and pressed against the card or envelop by the platen. In the upward movement of the plunger, the carriage is fed along the distance of one stamp by

the rack and pinion gear hereinabove described, and at the same time, the carriage is locked and prevented from being thrown back suddenly by means of the notched bar and the dog which engages said bar. This operation is kept up until the carriage reaches the final end of its throw, after the last stamp of the projecting row has been affixed to a card or envelop, whereupon the dog is tripped by the means described and held out of engagement with the notched bar 89, allowing the elastic band to return the carriage to the initial point of its throw.

It will thus be seen that the machine is automatic in action and may be operated with great rapidity, thus reducing the labor of affixing stamps to cards, envelopes and mail matter generally.

Having thus fully described the invention, 20 what is claimed as new is:—

1. A stamp affixing machine embodying a platen, and a table, means connected to said platen and table for moving the same simultaneously toward and from each other, 25 means for feeding stamps between said platen and table, means for severing the stamp, a carriage, and means for moving the carriage at right angles to the path of movement of the platen.
2. A stamp affixing machine comprising a table and a platen, means connected to said table and platen for positively moving the same toward and from each other, a carriage movable at right angles to the path of movement of the platen for feeding stamps successively between the platen and table, means for moving said carriage, and means for moistening the stamps preparatory to their entrance between the platen and table.
3. A stamp affixing machine comprising a table, a platen working in opposition thereto, said platen being mounted upon a plunger, said table being connected to a pivoted lever, connections between said lever and plunger whereby said platen and table are positively moved in opposite directions, a carriage movable at right angles to the path of movement of the platen to feed stamps successively between the platen and table, 45 presser rolls, moistening rolls, and means for moving said rolls toward and from each other.
4. A stamp affixing machine comprising a table, a platen, connections between said table and platen whereby they are operated positively and simultaneously, a carriage movable at right angles to the path of movement of the platen to feed stamps between the platen and table, rollers between which the stamps are fed, and means for moving said rollers apart to allow the stamps to be inserted between them.
5. A stamp affixing machine comprising a table, a platen, severing mechanism carried

by said platen, a lever connected to said table, a connecting rod attached to said lever, said rod being mounted in an arm extending from the platen operating mechanism whereby said platen and table are positively and simultaneously moved toward and from each other, a stamp carriage movable at right angles to the path of movement of the platen, said carriage embodying a roller upon which the stamp sheet is wound, and spring clips embracing said roller and adapted to confine 75 the stamp sheet thereon.

6. A stamp affixing machine embodying a table, a leg secured to said table and mounted to move in a guide, a lever pivoted to said leg and fulcrumed on the frame, a connecting 80 rod connected to said lever, a platen, a plunger to which said platen is connected, said plunger having an arm extending therefrom through which the connecting rod extends, whereby said table and platen are simultaneously and positively moved in opposite directions, and a severing device carried by said platen.

7. A stamp affixing machine embodying a table, a platen connected to a plunger, connections between said table and plunger whereby the platen and table are moved simultaneously toward and from each other, a stamp carriage movable at right angles to the path of movement of the plunger, a rack rail 95 connected with said carriage, a pinion engaging said rack rail, a shaft for said pinion, a second pinion having a clutch engagement with said shaft, and an actuating rack bar movable with the platen and coöperating 100 with the clutch pinion.

8. A stamp affixing machine embodying a table, a platen working in opposition thereto, a stamp carriage movable at a right angle to the path of movement of the platen, a rack 105 rail on said carriage, a pinion shaft having a pinion engaging said rack rail, a second pinion having a clutched engagement with said shaft, and an actuating rack bar meshing with said pinion and movable with the platen, 110 said rack bar being pivotally mounted so that it may be thrown out of mesh with the pinion.

9. A stamp affixing machine comprising a table, a platen working in opposition thereto, 115 a carriage movable at right angles to the path of movement of said platen and adapted to feed the stamps successively between the platen and table, means for moving said carriage intermittently, rollers between which the stamps are fed preparatory to their entrance between the platen and table, means for holding said rollers in contact and means for moving said rollers apart to allow the stamps to be inserted between the same.

10. In a machine of the character described, a table, a platen working in opposition to said table, a carriage, means for moving said

carriage at right angles to the path of movement of said platen to feed the stamps successively between the platen and table, said means comprising racks and pinions adapted to be simultaneously operated, rollers between which the stamps are fed preparatory to their entrance between the platen and table, means for moving said rollers apart to allow the stamps to be inserted between the

same, and means for holding said rollers in contact.

In testimony whereof, I affix my signature in presence of two witnesses.

GARFIELD O. THOMPSON.
